BOBBIN FOR DACRON FILAMENTS

Rawson Atwood, Buttonwood Lane, Rumson, N.J., and Charles C. L'Allemand, 168 The Fellsway, Murray Hill, N.J.

Filed Aug. 5, 1954, Ser. No. 447,942

1 Claim. (Cl. 242—118.31)

This invention relates to improvements in textile bobbins.

More particularly, the invention is concerned with bobbins or tubes of the type used for winding filaments or fibers for shipment to the user, and with bobbins which may be subjected to relatively severe service conditions.

The invention has for its general objects the production of a bobbin meeting a number of somewhat inconsistent requirements, the principal ones being: great strength combined with cheapness and lightness; a surface which, when cut or otherwise damaged, will not catch the yarn or fiber; and a high impact strength, particularly at the ends.

While the invention is not limited to such fields of use, its advantages will appear most clearly with reference to the winding of modern synthetics in low deniers, Dacron being a typical material illustrating very fully severe requirements for a bobbin and the satisfying thereof by the structure and method of the present invention. In the particular class of service contemplated it has heretofore been found necessary to utilize laminated phenolic or other thermo-setting synthetic resins or plastics, and moreover, to utilize special preforms in the molding, as well as to perform accurate grinding and other finishing operations. Even so, the success of these expensive bobbin structures has been a qualified one.

It is ordinarily not permissible to select bobbin dimensions in arriving at the best design, as the bobbin must be usable with existing mandrels, chucks or spindles, and is sometimes limited also by the method of winding of the fiber. For example, with the present commonly used method and machinery certain critical or "resonant" diameters are encountered, at which, in view of the angle of wind, the fibers of successive layers may lie close together in parallelism causing one fiber to catch another in unwinding, a condition known as "ribboning," thus creating danger of breakage of the fiber and, in an extreme case, the loss of the entire package. Such critical diameters may exist, for example, at close to two inches, four inches and eight inches, so that the package dimensions are confined to inner and outer diameters of about two and four inches, respectively, four and eight inches, respectively, etc. While the smaller diameter package permits a bobbin of inherently greater strength and lightness due to higher curvature, the quantity of fiber carried is only about one fourth as great, so that bobbin expense and weight may actually be greater per pound of fiber than with a larger diameter bobbin. Also, the sharpness of bend of the fiber in being laid onto a small diameter

2

bobbin is undesirable. For such reasons as these, the bobbin outer barrel diameter is not a matter of free choice, but is confined within rather narrow limits by the fiber manufacturer's requirements.

5 The fitting of existing mandrels requires a certain minimum inner bobbin diameter while the considerations above mentioned dictate the maximum outer diameter, with the result that the bobbin assumes the form of a rather large diameter thin-walled tube, which nevertheless must have great strength together with a surface of prescribed characteristics. The fulfilment of these requirements with a bobbin of substantially homogenous construction has been found difficult even at great expense, and the construction of a composite bobbin along known or conventional lines has hitherto been found impractical for very severe service conditions.

10 The bobbin of the present invention utilizes a steel, aluminum or other barrel member for obtaining the required strength, which may be increased by a forming operation such as beading, and obtains the required surface characteristics and impact strength by molding onto or around the steel or other shell a plastic cover extending beyond the ends to take impact and prevent deformation by impact of the steel or other structural shell.

15 25 In the drawing—

Fig. 1 is an isometric view of a bobbin embodying the invention in a preferred form;

Fig. 2 is an axial section of the bobbin of Fig. 1;

20 Fig. 3 is an enlarged section in an axial plan and showing the structure of one end of the bobbin barrel wall; Figs. 4 and 5 are views similar to Fig. 3, but on a smaller scale and showing modifications; and

25 30 Fig. 6 is a central axial section, largely schematic, and showing general arrangement of the mold, one end of which is shown in more detail and to a larger scale in Fig. 3.

The bobbin comprises a supporting shell or structural barrel element 10, which may be formed of steel, aluminum alloy, or other comparably strong material, and may 35 further be formed or beaded as shown for increasing the strength. Associated with the metallic shell 10 and preferably molded *in situ* thereon as an insert is a plastic coverall. The presently preferred plastic material, all 40 things considered, is thermo-plastic, modified polystyrene or styrene copolymer of the shock resistant or high impact type being very suitable. This material possesses the desired properties as outlined below in a high degree, but can, of course, be substituted by other covering materials wherever conditions permit or where somewhat 45 different properties may be required for the particular field of use. Nylon is suitable, but its use is not ordinarily justified, in view of its much higher cost.

50 55 In general, a primary requirement for a bobbin surface is a certain smoothness and softness, to prevent catching and breaking of the filament. High impact polystyrene, in common with a good many other materials possesses this property in a high degree. For example, the customary method of removing unused material from 60 a bobbin is to cut it by a longitudinal knife stroke, which also tends to cut or furrow the bobbin surface. The plastic material referred to, when so cut, does not cut deeply, does not form sharp burrs and may be burnished down with any round hard object so as to present again 65 a smooth surface which will not catch the filament. A

second requirement is sufficient strength to take the relatively high yarn pressures to which the material may be subjected. A third requirement is impact strength and elasticity sufficient to withstand dropping on to a concrete or other floor and also form a buffer or protection for the inner metal shell; the importance of this will appear more fully in the following description. Economy is, of course, a consideration and the material used is of relatively low cost in itself and adapted to inexpensive manufacture, since it molds in a fast thermo-plastic cycle, with a good surface finish and with a low percentage of rejects.

Referring now to Figs. 1, 2, 3, and 6 in some detail and more particularly to Figs. 3 and 6 which illustrate the method of formation, it will be observed that the bobbin may be molded in a thermo-plastic molding press, typically of the injection type, utilizing a pair of cavity dies 13 separating on an axial plane and a pair of cores 14 and 15 movable axially toward and away from each other and abutting along a line or plane 16 when in molding position. The mold may be gated at any of a plurality of convenient locations 17 for obtaining good flow of plastic and distribution of pressure within the mold. Gating at four points at the upper end of the mold (Fig. 6) has been found satisfactory in bobbins of sizes and proportions such as worked with so far.

The inner metal shell is supported from the mold core at each end, as shown in Fig. 3. As there shown, the core is generally cylindrical or formed with such draft angle as may be required in any particular case. Toward the end of the shell 10, for example, from the plane indicated at 20 to the plane 21 nearer the end of the shell 10, the core is tapered outwardly, and it is again tapered outwardly from plane 21 to the plane 22 at the end of the shell 10. At this point a shoulder 23 is formed, and is followed by a section between planes 22 and 24 which is beveled or tapered outwardly at a relatively sharp angle A, an angle of about 45°, as shown, being suitable. Below plane 24 the core is again substantially cylindrical, having only such draft angle as may be necessary for removal from the mold, and the molding surface of the core terminates in a rounded portion 25, cooperating with a similar rounded portion of the cavity mold parts 13, to form a rounded end on the bobbin.

For definiteness in description, the bobbin and its method of construction will be described with relation to specific dimensions of one actual size of bobbin, and its characteristics will be related to a bobbin of these dimensions and size, it being understood, however, that the invention is not limited to bobbins of this or any other particular size, but is applicable quite generally to bobbins of a great variety of dimensions and relative proportions.

In Fig. 3 of the drawing a variety of dimensions are indicated, by reference characters B to I inclusive. The overall length, in the construction shown (dimension I) may be about 4 inches, and extensive of the classic covering.

The length beyond the metal shell 10 (dimension H) may be about one-half inch or somewhat less, the length of the shell 10 being thus about 3 inches. The outside of the barrel in the construction shown is about 4 inches and the inside diameter C about three and five-eighth inches, giving the overall wall thickness of about three-sixteenths of an inch. The general extensional relationships may be obtained from the drawing, which is to scale, by knowing that the distance between planes 20 and 21 and between planes 21 and 22 is one-eighth of an inch. The inside diameter of the metal barrel element 10, dimension B, is about .005" greater than the core diameter at that point. The taper between planes 20 and 21 is relatively greater, being shown as .03 inch increase in diameter, while the taper between planes 21 and 22 may be very slight to only a few thousandths in-

crease in diameter to insure the right thickness or may even be eliminated. The increase in diameter between planes 22 and 24 is not great, amounting again to about another .03 inch and below this point the core is formed to only such slight draft angle as is necessary for molding purposes. The beaded metal shell 10 may be about 18 gauge thickness, or about .05 inch and varied in thickness according to requirements. In view of the beading, the thickness of the plastic covering on the outside of the barrel may range from a maximum of about one-eighth inch, as at 32 to a minimum of about one-sixteenth inch or somewhat less, as at 31, the minimum thickness in the construction shown being about .05 inch.

15 The tails 30 (Fig. 1) left at the gating points are ground off as desired, and the entire barrel surface may be ground to eliminate any flash at the mold parting lines, this being a simple center grinding operation. In the construction and method illustrated in Fig. 3, 20 the metal barrel 10 is selected with a length and inside diameter, so that it will fit between the plane 22 and corresponding plane in the other core member, and will be slightly expanded by the taper of the core, the precise degree of expansion varying with variation in 25 length and inside diameter of the member 10 within the permitted manufacturing tolerances. Ovality of the barrel member is thus corrected, arcuate centering with relation to the plastic cover is provided and a plastic-tight seal is provided to prevent plastic from entering the 30 space between the member 10 and the mold core elements.

Fig. 4 illustrates a modified form of mold and bobbin, which is identical with that just described except that the core elements are provided with grooves such 35 as the groove 39. Three or four of these grooves, distributed symmetrically around the axis of the core and bobbin may be provided. These grooves admit plastic into the interior of the member 10, covering the inside and also providing internal bearing ribs, 40, as indicated. 40 The ribs 40 may be removed, if desired.

Fig. 5 illustrates a further modification, in which a relatively thick metal barrel member 10', which may advantageously be made of aluminum alloy is provided. Commercially available extruded or drawn tubing is suitable. The metal shell 10' may comprise half the total barrel thickness, the remainder being plastic. The outer surface of member 10' is smooth and cylindrical, and concentric with the core, the outer molded surface of the barrel and with the inner surface 42 of the plastic beyond the end of member 10'. The end of barrel member 10' is formed to a radius as indicated at 41 so that the section of the plastic is gradually reduced between its thick end portion and its thin portion over the surface generally of the barrel 10'. The relationship of the edge of the member 10' to the core is the same as in the embodiment previously disclosed with reference to Fig. 3.

As stated above, a very important requirement in bobbins of the type disclosed is impact resistance, and it is found that a plastic cover extending beyond the end of the metal tube about three-eighths of an inch or thereabouts provides an extremely satisfactory buffer or impact protection for the metal barrel member. In both the form disclosed in Figs. 3 and 4 and that disclosed in Fig. 5, the configuration of the end of the metal barrel is such that the plastic thickness is reduced gradually, thus avoiding any undue concentration of flexing strain.

70 The length of the extension of the plastic beyond the ends of the metal barrel member may be varied considerably, and in general may conform to existing practice in the winding of the filament, so that the part of the barrel which has the fiber or filament wound upon 75 it, is backed up by the metal barrel member, and the

ends of the barrel where the plastic is not thus supported is left bare.

What is claimed is:

A textile bobbin comprising a beaded tubular metal barrel member and a plastic covering therefor extending beyond the ends thereof, the metal barrel member terminating at its ends at reduced diameter parts of the beading so that the section of the plastic is gradually reduced from the extreme end of the metal barrel member by comparison with its section beyond the end thereof, the plastic covering conforming internally to the outer surface of the metal barrel member and being externally cylindrical.
